UNITED STATES PATENT OFFICE.

DENNIS M. WILSON, OF MUNCIE, INDIANA, ASSIGNOR OF ONE-HALF TO FREDERICK S. SAUNDERS, OF MUNCIE, INDIANA.

IGNITION-TIMING DEVICE FOR MAGNETOS.

1,060,871.

Specification of Letters Patent.

Patented May 6, 1913.

Application filed April 21, 1911. Serial No. 622,558.

To all whom it may concern:

Be it known that I, DENNIS M. WILSON, citizen of the United States, residing at Muncie, in the county of Delaware and State 5 of Indiana, have invented certain new and useful Improvements in Ignition-Timing Devices for Magnetos, of which the following is a specification.

This invention relates to an improved 10 means for controlling the variation in the time of ignition in high tension circuits produced by magnetos employed in conjunction with internal combustion engines.

In the present ignition system for internal combustion engines in which magnetos are employed as an exciter to directly produce the high tension current without the use of induction coils, and in which the current distributers form a part of the magnetos and are driven directly therewith, the means employed to regulate the variation in the time of ignition comprises the advancing or the retarding of the contact breakers of the magnetos.

25 It is a known fact that in magnetos the point of maximum efficiency is obtained by interrupting the magnetic flux, or breaking the contact, when the armature poles lie substantially in parallelism with the poles of 30 the field magnet, and therefore when the contact breakers are advanced or retarded the magnetic flux or current is broken before or after the point of highest efficiency is reached. The tension of the current is 35 thus decreased and the spark between the electrodes is considerably lessened.

It is with the object of overcoming this decrease in the high tension circuit when varying the time of ignition, that this improved ignition timing device is designed.

Another object of this invention is to provide a coupling member between the engine and the magneto which may be adjusted during the operation of the engine to advance or retard the armature of the magneto with respect to the cylinders of the engine, producing an earlier or later spark.

A further object of this invention is to 50 provide the adjustable coupling, or ignition controlling device, with means whereby it may be operated at a point distanced from the engine and the magneto, as from the driver's seat of a motor vehicle, so that the speed of the engine may be varied without 55 decreasing the intensity of the spark.

For a full understanding of the invention and the merits thereof and also to acquire a knowledge of the details of construction, reference is to be had to the following description and accompanying drawings, in 60 which:

Figure 1 is a side elevation of the improved device applied to a magneto; Fig. 2 is a top plan view of the same; Fig. 3 is a longitudinal and central section through the device detached; Fig. 4 is a detail perspective view of one end of the coupling, partly in section and showing the parts separated from one another; Fig. 5 is a detail view of the coupling sleeve and the shifting ring carried thereby; and, Fig. 6 discloses a side elevation of the operating means employed.

Corresponding and like parts are referred to in the following description and indicated in all the views of the drawing by the same reference characters.

Referring to the drawings, 10 designates a magneto of any approved type having a spindle 11 formed with a cone 12 carrying 80 a retaining nut 13.

14 designates a driving shaft which is driven positively by the engine to which the magneto is coupled.

One embodiment of the invention is disclosed in the drawings where 15 and 16 designate a pair of driving collars. The collar 15 has a tapering bore into which is fitted a correspondingly shaped and relatively soft bushing 17 binding over the cone 12, 85 and being held in such position by the nut 13. The collar 16 is mounted upon the outer end of the magneto section 18 of a coupling shaft, the collars 15 and 16 being held in place by set screws 19 engaging respectively with the cone 12 and the shaft section 18. The collars 15 and 16 are formed at their adjacent ends with peripheral flanges 20 having laterally extending and diametrically opposed lugs 21 at their edges engaging in recesses 22 formed at right angles to one another in the opposite edges of a compensating ring 23.

The shaft section 18 is provided with a pin 24, formed preferably by reducing the 105 end of the section 18, which engages for rotation in a socket 25 formed in the driving section 26 of the coupling shaft. The pin 24 centers the two sections 18 and 26 of the coupling shaft. An outer socket 27 is car- 110

ried upon the opposite end of the driving section 26 receiving the end of the driving shaft 14 which is held therein by a set screw 28.

- 5 The shaft sections 18 and 26 are provided with studs 29 and 30, extending in opposite directions, and engaging in oppositely inclined spiral grooves 31 and 32 formed in the inner wall of a coupling sleeve 33, the 10 sleeve being arranged to rotate with the coupling sections. The sleeve 33 receives in its opposite ends the shaft sections 18 and 26, and is adapted for reciprocation there-over to move the studs 29 and 30 in the inclined grooves 31 and 32 respectively to turn the sections 18 and 26 in opposite directions. The sleeve 33 carries an annular bead 34 midway of its ends over which is rotatably fitted a shifting ring 35. The ring 35 is provided at one end with an inwardly extending flange 36, the marginal edge of which approaches the periphery of the sleeve 33. Raceways 37 are formed in the opposite faces of the bead 34 and in the inner face of 25 the flange 36 to receive bearing balls 38 adapted to take up the friction incident to the thrust of the shifting ring 35 when operated. The balls 38 are held against the outer side of the bead 34 by a gland 39 threaded into the open end of the ring 35 and having a raceway 40 which supports other bearing balls 40'. The gland 39 is flanged, as at 41, the flange carrying set screws 42 binding against the outer face of 35 the ring 35 to hold the gland when adjusted. The ring 35 is provided, at diametrically opposite points, with outstanding studs 43, one of which is preferably detachable, projecting into elongated openings 44 formed in the 40 ends of a fork 45. The fork 45 is carried upon a shifting lever 46 fulcrumed at 47 upon a suitable support 48, preferably being a projection from the crank case of the engine.
- 45 Any suitable operating means may be employed for swinging the lever 46, for instance; as shown in the drawings, a connecting rod 49 is hinged to the outer end of the lever 46 and is pivoted at its opposite ends 50 to a hand lever 50 mounted upon a suitable support 51. A segment 52, concentric to the hand lever 50 co-operates with a pawl 53 carried upon the lever 50 to lock the same in adjusted position.
- 55 In the use of the improved timing device, the sleeve 33 is moved into its normal posi-

tion, or directly over the meeting ends of the shaft sections 18 and 26. The driving collar 15 is loosened upon the cone 12 and the magneto spindle 11 is adjusted in the usual manner with respect to the positions of the pistons in the engine, when the collar 15 is again clamped in position to positively drive the magneto from the engine. The engine is now set in motion, the magneto being adjusted to produce its maximum spark. 60

When it is desired to increase or decrease the speed of the engine, the adjustment of the magneto itself is not altered, but the sleeve 33 is moved over the shaft sections 18 70 and 26 in the desired direction, whereupon the studs 29 and 30 are caused to move through the oppositely inclined grooves 31 and 32 to rotate the shafts in opposite directions with respect to one another. This 75 movement of the sleeve 33 alters the adjustment between the magneto spindle and the pistons of the engine, producing an earlier or a later spark as required without varying the intensity of the spark or decreasing the 80 efficiency of the magneto.

Having thus described the invention, what is claimed is:

In a device of the class described, coaxing shafts arranged end to end and each having 85 a stud extending laterally therefrom, a sleeve slidable over the contiguous portions of said shafts and provided with interior grooves engaging respectively over said studs, said grooves extending obliquely to 90 the longitudinal plane of the shafts and reversely arranged, an annular rib carried by said sleeve; a collar mounted upon said sleeve and including an annular channel engaging over said rib, means for moving said collar 95 longitudinally of the shafts to cause the sleeve to impart a partial rotation to one of said shafts relative to the other shaft, a clutch member connected to one of said shafts, another clutch member adapted to be 100 coupled to the mechanism to be actuated, and a compensating member located between the clutch members and including oppositely directed clutch faces engaging both of said clutch members. 105

In testimony whereof, I affix my signature in presence of two witnesses.

DENNIS M. WILSON. [L. S.]
